No. 657,506.

Patented Sept. 11, 1900.

R. J. BARRY.

BRIDGE ALARM FOR TRAINMEN.

(Application filed June 29, 1899.)

(No Model.)

UNITED STATES PATENT OFFICE.

ROBERT J. BARRY, OF BANGOR, MAINE, ASSIGNOR OF ONE-HALF TO
CHARLES CULLINAN, OF SAME PLACE.

BRIDGE-ALARM FOR TRAINMEN.

SPECIFICATION forming part of Letters Patent No. 657,506, dated September 11, 1900.

Application filed June 29, 1899. Serial No. 722,316. (No model.)

To all whom it may concern:

Be it known that I, ROBERT J. BARRY, a citizen of the United States, residing at Bangor, in the county of Penobscot and State of Maine, have invented a new and useful Bridge-Alarm for Trainmen, of which the following is a specification.

My invention relates to alarms intended to notify trainmen of freight-trains of the approach of the train to overhead bridges.

The object of the invention is to provide an improved alarm mechanism of this class, simple, cheap, durable, and efficient, which shall be operated by passing cars and continuously operated by each succeeding wheel of the cars of the train, thereby effectually calling attention and eliminating accidents in striking bridges due to a lack of notice of the approach of the train to them.

With this object in view my invention consists in the improved construction, arrangement, and combination of parts hereinafter fully described and afterward specifically pointed out in the claim.

In order to enable others skilled in the art to which my invention most nearly appertains to make and use the same, I will now proceed to describe its construction and operation, reference being had to the accompanying drawings, forming part hereof, in which—

Figure 1 is a perspective view of an alarm mechanism constructed in accordance with my invention. Fig. 2 is a vertical sectional view on a plane cutting transversely through the rail just inside of the framework of the alarm mechanism, with a fragment of a car-wheel in position operating the alarm. Fig. 3 is a vertical sectional view on the plane indicated by the broken line 3 3 of Fig. 2 looking in the direction of the arrow.

Like letters of reference mark the same parts wherever they appear in the several figures of the drawings.

Referring to the drawings by letters, A indicates one rail of a railway, and B B cross-ties or beams, each of which extends some distance beyond the rail and supports an upright C at its outer end. The cross-beams B are connected by a cross-rod B', and the up-

rights C C by a cross-rod C' and a top cross-bar C''.

D indicates a bridge-piece connecting the cross-beams B B at the outer side of rail A, recessed on top (shown at D') and bored vertically to receive a vertical rod E, carrying a shoe F at its upper end, said shoe being held at its normal height, projecting slightly above the top of the rail, by a spring G, coiled about the rod E, and having its upper and lower bearings against the under side of the shoe F and the upper side of the bridge D, respectively. The shoe is beveled off at its front and rear, as at F' F', and provided at its center with a depending projection F² to fit in the recess in the bridge and act as a guide when the shoe is depressed.

On the cross-rod B' is pivoted a lever G, pivotally connected at its inner end to the rod E and at its outer end in the lower bifurcated end of a vertical bar H. In the upper bifurcated end of bar H is pivotally connected one end of a lever I, pivoted on the cross-rod C', the other end of lever I being turned upward at I'. To the upturned end I' of lever I is secured a spring bar or rod J, carrying a bell hammer or clapper K at its upper end. This bell-clapper K projects into a bell L, hung at the outer end of a spring-bar M, secured to the cross-bar C''. The rod E is rigidly secured to the projection of the shoe in such a position as to extend through the vertical opening in the bridge, and the spring fits loosely around the pin, thereby making a very simple and cheap construction. In assembling the parts the spring is placed in the recess and the shoe placed in position, with the pin projecting through the spring and through the perforation in the bridge in position to be secured to the end of the lever G'.

The construction of my invention will be readily understood from the foregoing description, and its operation may be described as follows: The alarm mechanism being located near an overhead bridge, in either direction therefrom, the wheel, as at N, of a passing car will depress the shoe F, which will carry down with it the rod E and the inner end of lever G, elevating its outer end, the bar H,

and the inner end of lever I. This will move the rod J and bell-hammer K outward, causing it to strike the bell and sound an alarm. The spring G will elevate the shoe F after the wheel N passes off the shoe, thus reversing the movement of the levers, bar, and bell-hammer, causing the latter to strike the opposite side of the bell, repeating the alarm, and the alarm will be repeated as each wheel 10 of every car in the train depresses and releases the shoe F. In this manner the alarm will be sounded continuously until the entire train has passed, notifying the trainmen on every part of the train of the approach of an 15 overhead bridge.

The whole mechanism, except the shoe and bell, may be boxed in to protect it from injury from various causes and from the interruption to its working which might be caused 20 by snow, ice, or sleet.

While I have illustrated and described what I consider to be the best means now known to me for carrying out my invention, I do not wish to be understood as restricting myself 25 to the exact forms and constructions shown, as many slight changes therein or variations therefrom might suggest themselves to the or-

dinary mechanic, all of which would be clearly included within the limit and scope of my invention.

Having thus fully described my invention, what I claim as new, and desire to secure by Letters Patent of the United States, is—

In a signal, the combination, with a vertically-perforated bridge, the top of which is recessed at the perforation, of a shoe, the ends of which are beveled and the central portion is provided with a depending projection to fit in the recess of the bridge, a pin rigidly secured to the projection in position to extend through the perforation, a spring in the recess around the pin, a lever secured to the projecting end of the pin, a standard, a spring-supported bell on top of the standard, a lever pivotally secured to the standard, one end of which is provided with a spring-supported clapper in position to engage with the bell, and a link-bar connecting the other end of the lever with the lever that is secured to the pin. 35 40 45

ROBERT J. BARRY.
